CLAIM

The ornamental design for a combined fluid bottle and case for eyeglasses and contact lenses, substantially as shown and described.

DESCRIPTION

FIG. 1 is a front elevational view of a combined fluid bottle and case for eyeglasses and contact lenses showing my new design;

FIG. 2 is a right side elevational view thereof;

FIG. 3 is a rear elevational view thereof;

FIG. 4 is a top plan view thereof;

FIG. 5 is a bottom plan view thereof; and

FIG. 6 is a perspective view thereof; shown open.

The broken lines shown in FIGS. 1, 3, 4, 5 and 6 represent conventional stitching.
